CLAIM

The ornamental design for a shoe insole, as shown and described.

DESCRIPTION

The patent or application file contains at least one drawing executed in color. Copies of this patent or patent application publication with color drawing(s) will be provided by the Office upon request and payment of the necessary fee.

The FIGURE is a bottom planar view of a shoe insole showing my new design.

The dash-dot-dash broken line illustrates a boundary that forms no part of the claimed design. The remaining even dashed broken lines depict portions of a shoe insole that form no part of the claimed design.
